UNITED STATES PATENT OFFICE.

ELI F. BRICKELL, OF BRADFORD, PENNSYLVANIA.

VENTILATING-SASH LOCK.

Application filed September 22, 1921. Serial No. 502,396.

To all whom it may concern:

Be it known that I, ELI F. BRICKELL, a citizen of the United States, residing at Bradford, in the county of McKean and 5 State of Pennsylvania, have invented a Ventilating-Sash Lock, of which the following is a full and complete specification.

The primary object of my invention is to provide a simple, neat and inexpensive sash lock comprising fixtures which may be readily and conveniently attached to the upper and lower sliding sashes of a window for securely locking them when the window is closed, and adapted also for operation to 15 safely lock said sashes when either one is slightly moved to open the window for the purpose of ventilation.

This principal object of my invention is accomplished in the present instance by 20 means of a fixture or pivoted locking-bar attached to a side rail of the upper sash and having a limited swinging movement from an approximately vertical position to a horizontal position, in combination with a fixture or engaging plate on the upper part of 25 the lower sash; whereby when the window is closed the sashes will be securely locked in this position by engagement of the fixture on the lower sash with the outer end of the 30 depending locking-bar carried by the upper sash, and when it is desired to partly open the window for the purpose of ventilation—by either slightly raising the lower sash or lowering the upper sash—the locking-bar 35 may be swung outward to firmly and safely lock said sashes against further movement by engagement of the fixture on the lower sash with the inner or pivoted end of said locking-bar.

40 My invention consists, therefore, in the particular construction and arrangement of the fixtures comprising the device for locking the sashes of a window in both a closed and slightly open position; all as hereinafter 45 fully described and specifically set forth in the claims.

In the accompanying drawings, forming a part hereof:—

Fig. 1 is a front elevation illustrating the 50 application of my invention.

Fig. 2 is an enlarged front elevation of the sash-lock applied with the parts or fixtures in normal position and the sashes in closed position.

55 Fig. 3 is a vertical sectional view through

the window sashes to show the sash lock in side elevation.

Fig. 4 is a detail view of the plate for supporting the locking-bar and limiting its swinging movement. 60

Fig. 5 is a view of the locking-bar detached from its supporting plate.

Fig. 6 is a vertical sectional view through the locking-bar and its attaching-plate, with the locking-bar disposed in its horizontal 65 position.

As illustrated in the drawings my invention is applied to that conventional type of window in which are employed upper and 70 lower sashes 10 and 11 slidable in a frame in the usual manner, and the device which I employ for locking the sashes closed or slightly open comprises a fixture or swinging locking-bar 12 pivoted at its upper end in an attaching-plate 13 fastened to a side rail 75 10^a of the upper sash 10 and a fixture or bent plate 14 secured on the upper rail 11^a of the lower sash in alignment with the aforesaid swinging-bar, so that said plate may engage the outer end of the swinging locking-bar 80 in its depending position to lock the sashes against movement when the window is closed (see full lines, Fig. 3) and may also engage the inner portion or pivot end of said swinging locking-bar when the latter is swung 85 outward and the sashes moved to open the window (see dotted lines, Fig. 3); it being understood that the attaching-plate which carries the locking-bar is provided with means, hereinafter particularly described, 90 for limiting the upward swinging movement of said locking-bar so that it may form a stop against any further movement of the sashes with respect to each other. 95

In the present instance the attaching-plate 95 is provided with holes to receive the screws 15 and at its lower end with spaced apart ears 16, 16, forming the bearings for the swinging locking-bar 12, with a transverse shoulder 17 between the upper part of the 100 ears so as to limit the upward swinging movement of said bar, as indicated in Fig. 6, and I prefer to make the locking-bar or stop device, carried by this plate, of a metal bar bent upon itself with the terminals 105 turned abruptly outward to form pivots or gudgeons 12^a, 12^a, by which said locking-bar is pivoted in the ears 16 of the plate. The looped end of the rod forming the locking-bar is the outer end when said bar is pivoted 110

in the plate, and as the rod is of spring metal the free ends thereof on which the gudgeons are formed may be brought together in pivotally connecting the locking-bar to the ears on the attaching-plate.

The fixture which is adapted to cooperate with the locking-bar consists of a plate 14 having holes for the attaching-screws and an upturned inner end 14^a forming a stop 10 to limit the inward movement of the depending locking-bar when the sashes are closed and also an engaging portion which bears against the inner portion of said locking-bar, near its pivot, when the bar is 15 swung outward and the lower sash moved to the partly open position shown in dotted lines Fig. 3.

In attaching the two fixtures constituting my ventilating sash-lock the bent 20 plate 14 is first applied by securing the same on the meeting-rail 11^a of the lower sash 11 immediately in front of one of the side rails 10^a of the upper sash 10, so that the upturned inner end 14^a of the plate 25 will be at the inner edge of the aforesaid rail 11^a. Before attaching the other fixture the sashes are moved to closed position and the attaching-plate 13 carrying the pivoted locking-bar is adjusted on the 30 side rail 10^a of the upper sash so that the outer end of said locking-bar when lowered will engage with or be in close proximity to the plate 14 directly in front of the upturned rear end thereof, and when so adjusted the said attaching-plate is secured 35 in place by the screws 15.

In operation, when the window is closed the locking-bar being suspended from the attaching-plate by its pivotal connection 40 therewith will engage at its lower end the plate 14 on the lower sash and thereby lock the sashes against being moved to any extent. When it is desired to open the window for the purpose of ventilating the 45 room, the upper sash may be lowered to a certain extent, or the lower sash raised, by moving the locking-bar outward and sliding the sash until the upturned inner end of the plate 14 bears against the inner portion 50 of the locking-bar, which latter then bears against the shoulder 17 and prevents

further opening movement of the sashes. Of course the length of the locking-bar, or distance between the plates 13 and 14, determines the extent to which the window 55 may be opened, and as it is the purpose of the device to prevent the window from being opened sufficiently to allow a person to enter through the same the length of 60 the swinging bar should be such as to permit the window to be opened only slightly, as for instance to the extent indicated in the drawings. The lock therefore provides a safe means by which the window may be 65 partly opened to ventilate a room, and as the locking-bar drops by gravity when the window is closed the operation of locking the sashes in closed position is automatic, as will be understood.

When it is desired to fully open the window it is necessary only to first detach the locking-bar by disengaging it from the pivot-ears of the attaching-plate 13, thus removing the stop device and permitting 75 the plates to pass each other. It will be noted, however, that when the locking-bar is in place it becomes a positive stop-device to effectually prevent movement of the sashes beyond a limited extent, and therefore provides a safe ventilating sash-lock.

Having described my invention, I claim:

1. A ventilating sash-lock comprising an attaching-plate having spaced apart ears with a stop-shoulder between the upper part 80 of said ears, and a locking-bar pivoted between the ears of the attaching-plate to normally depend therefrom and limited in its upward movement by engaging the stop-shoulder, substantially as shown and 90 for the purpose set forth.

2. A ventilating sash-lock comprising an attaching-plate having spaced apart ears with a shoulder between the upper part of 95 said ears and a locking-bar pivoted at one end in said ears; said plate and bar being for attachment to a side rail of the upper sash; together with a plate having an upwardly turned rear end, the last mentioned plate being for attachment to the upper 100 end of the lower sash.

ELI F. BRICKELL.
